UNITED STATES PATENT OFFICE.

MACKINTOSH HUTCHINSON, OF PHILADELPHIA, PENNSYLVANIA.

WOODWORKING MACHINE.

Application filed April 12, 1922. Serial No. 551,892.

My invention relates to wood-working machines. It has for its object to provide a construction in which the machine combines a cross cut saw, a rip saw, and a jointer, the 5 machine being formed so that the several operations mentioned may be carried on in the same machine, and the several parts arranged to combine strength, stability and simplicity; and in which also simple and 10 efficient means will be provided for changing the position of the work-table so that it may be readily adjusted for coaction with either the cross-cut saw or rip saw, and which may also be readily adjusted to stand at an angle 15 or inclination to the saw for facilitating the work under desirable conditions. To the accomplishment of the foregoing and such other objects as may hereinafter appear the invention consists in the features of construction and combination of parts hereinafter described and then sought to be clearly defined by the claims, reference being had to the accompanying drawings forming a part hereof, and in which

25 Figure 1 is a plan view of the machine, the position of the motor for operating the rip saw being shown in dotted lines;

Figure 2 is a side elevation of the machine, a tilted position of the work table being 30 shown in dotted lines;

Figure 3 is an end elevation of the machine.

In the drawings the numeral 1 designates the frame of the machine consisting of the 35 metal side members 2 connected one to the other by cross-bars 3 which may be wooden bars bolted to the side members, the side members having extending brackets 4 to receive the work-table supporting and adjusting means, and the side members supporting a saddle 5 extending from one side member to the other, preferably midway of the two members, and from which forwardly extends a bracket arm 6 carrying at one end a journal-bearing 7 for the rip saw shaft, the other journal bearing 8 for said shaft preferably being formed as a part of the saddle 5. From the saddle 5 is supported an upright post 9, the lower end of which passes through a 45 split collar or sleeve 10 preferably attached to or formed as a part of a rib or web 11 of the saddle and formed with threaded ears or lugs 12 to receive the threaded end of a rod 13 provided with an operating handle, 50 which may be a hand wheel 14, so that the post may be clamped in position by contract-

ing the split collar. A shoulder 15 formed by reducing the diameter of the post, or otherwise, rests upon a collar 16 which encircles the post and may be seated on the 60 saddle 5 or other part of the machine frame and is formed with a finger 17 through which passes a pin 18 adapted to engage any one of a number of perforations 19 formed at predetermined distances apart in a semi-circular boss 20 which may be formed as a part 65 of the machine frame or saddle. The finger 17 and the boss 20 serve as an index scale in rotatable adjustment of the post for causing the cross-cut saw to operate on the work at different angles to which it may be adjusted for cutting either square or at any angle to the right or to the left for which the adjustment is made; the slide pin passing through the finger and entering one of the perforations in the boss will hold the post at the adjustment given thereto. If a cut at an angle other than that provided for by the perforations in the boss is desired, the same can be effected by removing the pin and loosening 70 the split collar 10 by manipulation of the threaded rod 13 and after obtaining the adjustment then tightening the split clamp on the rotatable post so as to hold the post to its adjustment. It is obvious that the post 75 may be held to its adjustment by the split collar or sleeve and the threaded operating rod without the use of the pin in conjunction with the index finger and perforations 80 in the boss; and that if the split collar or sleeve be left in an unclamped condition the index finger and pin for entering the perforations of the boss may be relied on for holding the post to its adjustment. In either 85 case the index scale will indicate the extent of adjustment made. The collar 16 from 90 which the index finger extends may be secured to the post by a set screw 21.

The upper end of post 9 carries a laterally extending bracket arm 22 which is supported from the post by a hub 23 formed with side bearings or boxes 24 and at its outer end carries a cross-head 25 formed with side bearings or boxes 26, said bearings or boxes 24 and 26 serving to support slide rods 27 which constitute a sliding carriage or beam that supports at one end a motor 28, preferably an electric motor, for driving the saws and a jointer of the machine, said motor resting on a platform 29 suitably connected with the rods 27, and the other end of the carriage or sliding beam-rod having

a hand grip 30 for reciprocating the carriage and also provided with journal bearings 31 for the arbor shaft 32 of the cross cut saw 33. If desired, the journal boxes 24 and 26 5 may be provided with roller bearings 34 for the carriage rods or beams.

The saw arbor 32 carries a pulley 33^a from which a drive bolt 34 extends to and around a double cone pulley 35 mounted on the 10 shaft 36 of the motor 28.

The rip saw is designated by the numeral 37 and is mounted on the shaft or arbor 38 journaled in the boxes 7 and 8 and provided at one end with a pulley 39 designed to 15 receive a drive belt 40 which will pass around motor shaft pulley 35 when the motor is shifted to the position indicated by dotted lines in Fig. 1 by loosening the split sleeve or collar which holds the post 9 in 20 position. It will be observed that the mandrels of the rip saw and the cross cut saw stand at right angles to each other and that one saw operates in a plane lower than the other, and in the use of each the same work 25 table is used without any change in position of the table except to raise or lower it to bring it within the proper plane for the particular saw to be used.

The work table, designated by the numeral 41 is supported from the brackets 4 by screws 42 passing through sleeves 43 and provided with nuts 44 fitting between the upper and lower members of each pair of sleeves, each nut being provided with a bevel 35 gear 45 with which mesh bevel gears 46 mounted on a counter shaft 47 having its ends in bearings 48 formed on the sides of sleeves 43 and provided with a hand wheel 49 to turn the counter shaft to raise or lower 40 the screws and the table supported thereby. When the cross cut saw is in use the table is in the elevated position indicated in Figs. 1 and 3, and when the rip saw is to be used the table is lowered by the screws 42 so as 45 to bring it into the proper plane for action of the rip saw. The work table is connected with the screws 42 by means of segmental sockets 50 attached to a plate 51 secured to the underside of the table and which receive 50 rails or tracks 52 provided with depending ears or lugs 53 which fit within the bifurcations of heads or members 54 secured to the upper ends of the screws 42 and held therein by threaded bolts 55 passed through the 55 heads and rail lugs and tightened by hand-nuts 56 so as to clamp the lugs of the rails and hold the work table in its adjusted position, either horizontally or at an inclination as desired. The lugs 53 are formed with 60 tail extensions 57 through which screws 58 are passed with their ends adapted to bear against the heads 54 and they serve as stops to check the movement of the table when changed from an inclined to a horizontal 65 position and thus insure the prompt leveling

of the table when changing its position. The work table is also capable of adjustment towards and from the post 9 by sliding it along its rails 52 or track and locking it to such adjustment by a set screw 59 passing 70 through one of the segmental sockets 50 and biting against the rail.

A jointing device, designated by the numeral 60, is shown in a conventional way as any approved construction of such device 75 may be used. This is supported on a platform 61 and its driving shaft 62 is provided with a pulley 63 from which a belt 64 will extend to and around a pulley 35 on the shaft of the motor when the motor is shifted to the position shown in dotted lines in Figure 1 of the drawing. In this position the jointer and the rip saw may be operated at the same time.

The carriage which carries the motor 28 and cross cut saw may, if desired, be locked at any particular point in its length of travel, by means of a set screw 65 passing through one of the boxings 24 and made to bite against the rail 27 of the carriage. 85

Having described my invention and set forth its merits what I claim is:

1. In a woodworking machine comprising a saw and means for driving the same; a work supporting table beneath the saw, a 95 track upon which the table is adjustable laterally, spaced apart screws with which said track is connected for raising and lowering the table, two-part member sleeves through which the screws pass, nuts in 100 threaded engagement with said screws and disposed between the members of the sleeves, gears connected to said nuts, and a counter-shaft fitting at opposite ends in sockets formed as a part of the two-part 105 member sleeves provided with gears coacting with the gears of said nuts for simultaneously adjusting both screws for raising or lowering the table.

2. In a woodworking machine comprising 110 a saw and means for driving the same; a work supporting table beneath the saw, track-receiving sockets rigidly secured to the underside of the table, a track-rail fitted in said sockets and formed with depending lugs 115 and upon which the table is supported, screws for raising and lowering the table, bifurcated heads carried by said screws and receiving the depending lugs of the track-rails, means for clamping said lugs in said 120 heads to secure the work table at desired inclinations, and means for raising and lowering the screws for positioning the table at the desired elevation.

3. In a woodworking machine comprising 125 a saw and means for driving the same; a work supporting table beneath the saw, a track upon which the table is supported, screws for raising and lowering the table, lugs depending from the table track and fitting 130

in bifurcated heads carried by said screws, said lugs having tail extensions through which screws pass for leveling the table, means for clamping said lugs in said heads 5 to hold the table in position, and means for raising and lowering the screws for positioning the table at the desired elevation.

4. A woodworking machine, comprising a lower frame provided with a bridge-member 10 spanning the space between opposite sides of the frame and formed with a depending web, a laterally extending arm formed as a part of the web and provided at its outer end with a journal-bearing for a shaft, a a 15 journal-bearing extended laterally from the opposite side of the web for another part of the shaft, a shaft journaled in said bearings and carrying a rip-saw at its outer end positioned beneath a work-table, means for 20 supporting said table above the rip-saw,

and an upright rotatable post carrying at its upper end a traveling beam-member, an arm extending laterally from the upper end of the post and provided at its outer end with a sleeve to receive the slidable beam, 25 a tubular guide for the slidable beam positioned at the top of the upright post in which the beam is slidable, a motor supported upon one end of the slidable beam and a working tool carried by the other end of the beam and driven from the motor, the rotation of the upright post permitting change of operative position of the tool at the end of the slidable beam relatively to the rip-saw positioned beneath the work-table. 30 35

In testimony whereof I affix my signature.

MACKINTOSH HUTCHINSON.
